COMBINED COSMETICS BLENDER, INGREDIENT HOLDERS AND STAND THEREFOR

Monte L. Levin, New York, N.Y., and Samuel Bernstein, West Hartford, Conn., assignors to Dynamics Corporation of America, Waring Products Division, New Hartford, Conn., a corporation of New York

Filed Dec. 2, 1968, Ser. No. 14,736

Term of patent 14 years

Int. Cl. D28—99

U.S. Cl. D86—10

FIG. 1

FIG. 2

FIG. 3

FIG. 4

FIG. 1 is a perspective view of a combined cosmetics blender, ingredient holders and stand therefor showing our new design;

FIG. 2 is a top plan view;

FIG. 3 is a side elevational view; and

FIG. 4 is a front elevational view thereof.

We claim:

The ornamental design for a combined cosmetics blender, ingredient holders and stand therefor, as shown.
